UNITED STATES PATENT OFFICE.

CLAYTON B. McELWAINE, OF DRUMRIGHT, OKLAHOMA.

WELL-PUMP JACK.

1,261,573.

Specification of Letters Patent.

Patented Apr. 2, 1918.

Application filed May 11, 1917. Serial No. 168,007.

To all whom it may concern:

Be it known that I, CLAYTON B. McELWAINE, a citizen of the United States, residing at Drumright, in the county of Creek 5 and State of Oklahoma, have invented new and useful Improvements in Well-Pump Jacks, of which the following is a specification.

This invention relates to improvements in 10 pumping devices, and has particular reference to an improved pumping jack for operating oil well and similar pumps.

In pumping jacks as hitherto constructed the beam at the point of attachment to the 15 pump rod describes an arcuate path, and the rod is constrained to follow such arc, whereby it is continually subjected to lateral stresses, and undesirable wear and strain on the stuffing box and other parts of the mechanism 20 results. It is therefore my purpose in carrying out this invention to provide a pumping jack wherein the beam at the point of attachment to the rod will traverse a rectilinear path. It is my further intention to 25 furnish improved relative arrangements for the parts of the jack; and to make provision for more efficient oscillatory actuation of the beam by the power device provided.

With these and other objects in view I 30 have embodied my invention in the form described in the specifications and claims and shown in the accompanying drawings, in which—

Figure 1 represents a side elevation of the 35 preferred form of the invention.

Fig. 2 is a plan view of the same.

Fig. 3 is a fragmentary view of the beam and supporting structure, and illustrates means whereby the beam may be sustained 40 by the support.

Fig. 4 is a side elevation of a modification showing a method for oscillating the beam which I may utilize in some instances.

Fig. 5 represents another modification as 45 shown in side elevation.

Fig. 6 is a plan view of the same.

Fig. 7 illustrates in detail the supporting device shown in Fig. 5.

Referring to the drawings more particularly, and with especial reference to Figs. 50 1, 2, and 3, the upper portion of an oil well casing 1 is delineated therein, having the mouth provided with a stuffing box 2; and extending downwardly therethrough for actuation 55 of a pump disposed within the well, is a pump rod 3, terminating at a convenient

point above the stuffing box in means, shown as trunnions 4, for pivotal attachment to the beam 5; such arrangements being similar to those commonly adopted and needing no detailed description. In the present instance the beam 5 is bifurcated toward the outer end to receive the pump rod 3, and is formed transversely in the upper surface of the bifurcated portion 6 with a hollow 7 wherein 60 the trunnions are journaled, and which may or may not have caps to retain the trunnions therein. The beam extends laterally for connection to a suitable supporting structure 8, and in this form of my invention the 65 structure 8 is formed longitudinally with a slot 9 for reception of the beam. For suspension of the beam I provide a link 10 having pivotal attachment at the lower extremity to a pin 11 or other suitable securing 70 device extending transversely through the support 8 and the slot 9, and having pivotal attachment at the upper extremity to the beam at a point toward the pump; whereby it is disposed angularly to the support 8. 75 Such lower attachment is here indicated as a hook 12 constituting the extremity of the link and extending within a slot 13 therewith the beam is formed vertically, for engagement with a pin 14 inserted in the beam 80 85 transversely thereof.

On the beam I place a cam, adapted to engage a track in the oscillatory motion of the beam, whereby the beam will be forced outwardly from the support on passing the 90 center of the stroke, to maintain the trunnion bearing 7 in alinement with the pump rod 3. In the present instance duplicate cams 15 are secured in any suitable manner on either side of the beam 5 adjacent the 95 support 8, the face of which constitutes the track; and are maintained in contact therewith by the weight of the pump rod and the angular disposition of the link 10, the pitman 17' hereinafter described constituting a 100 fulcrum.

For actuation of the beam, the usual V member or jack 16 may be employed, having a horizontal arm 17 and a vertical arm 18 suitably braced, and adapted for rocking 105 movement by a downward prolongation 19 of the vertical arm 18, preferably terminating in trunnions 20, having bearings in a lateral extension 21 of the base of the supporting structure 8.

The jack is disposed for movement in a plane parallel to that of the beam, and at

the outer extremity of the horizontal arm 17 is pivotally attached a link or pitman 17', similarly connected at the upper end to the beam, whereby the beam may be actuated in accordance with movements of the jack 16.

The vertical arm 18 is adapted in the usual manner for attachment of a wire or rod whereby it may be operated by a pumping engine.

10 Under some circumstances I may employ the modification illustrated in Fig. 4. In this form of my invention, the V member or jack 16 and the pitman 17' as shown in Fig. 1, are dispensed with and the beam is formed 15 with a prolongation 22 beyond the support 8, having the end adapted for attachment of a flexible tension element, as for instance a wire cable 23 which may be terminally connected for oscillation of the beam to a 20 pumping engine in the usual manner. A sheave 24 or other suitable friction reducing device for guiding and maintaining the tension element 23 in position is disposed beneath the beam, and is properly journaled in 25 a mounting 25, which may be anchored as shown in the drawing or otherwise retained in position. It will be noted that the link 10 is attached upwardly from the beam to compensate for the absence of the pitman 17'.

30 A further modification of my invention is illustrated in Fig. 5. In this instance, lateral pivot members 26 are attached to the beam adjacent the cams 15 for sliding movement in slotted openings 27 inclosed by horizontal guides 27' extending between and secured to vertical supports 28. The cams 15 preferably engage the supports 28 remote from the pump rod 3; and in this form of my invention the pitman 17' is inclined to 35 40 ward the support 28, whereby the weight of the beam maintains the cams in such engagement. For actuation of the pitman a jack 16 is provided, similar to that shown in Figs. 1 and 2.

45 While I have here shown and described preferred forms of my invention for purposes of illustration, such embodiments are not to be interpreted as in any way limiting the spirit of the invention, it being apparent 50 that many and varied forms may be constructed without exceeding the scope thereof.

I claim—

1. In a device of the class described, a lever, a supporting structure, means for oscillating said lever, a link having one end

movably attached to the lever and having the other end attached to said support, and a cam on the lever adapted to engage a track to limit a point in said lever to rectilinear movement.

60

2. In a device of the class described, a lever, a supporting structure, means for oscillating said lever, a track, a link having one end attached to the lever and having the other end attached to said support, and a cam on the lever adapted to engage the track to limit a point in said lever to rectilinear movement; said link having an inclined position relative to the lever whereby said cam is maintained in engagement with 70 said track.

65

3. In a device of the class described, a lever, a supporting structure, means for oscillating said lever, a pump rod adapted for longitudinal movement by the lever, a link 75 having one end attached to the lever and having the other end attached to said support, and a cam on the lever adapted to engage a track to prevent lateral movement of said pump rod.

70

4. In a device of the class described, a lever, a support for one end of the lever adapted to permit longitudinal movement thereof, a cam on the lever, a track adapted to be engaged by said cam, and means for 85 retaining said cam in engagement with said track, said means consisting of a member adapted to support the other end of said lever, said member having an inclined position relative to said lever.

80

5. In a device of the class described, a lever having a transverse member, guides adapted to permit lateral sliding movement of said transverse member, a cam on the lever and a track adapted to be engaged by said cam; link means for supporting and oscillating said lever, said link means having an inclined position relative to said lever whereby said cam is maintained in engagement with said track.

95

6. In a device of the class described, a lever, a supporting structure, means for oscillating said lever, a link having one end attached to said support, a hook on its other end connected with the lever, and a cam on the lever adapted to engage a track on the supporting structure.

100

In testimony whereof I affix my signature.

CLAYTON B. McELWAINE.
